(57) **CLAIM**

The ornamental design for a container securing device as shown and described.

DESCRIPTION

FIG. 1 is a front elevation view of a container securing device showing my new design.

FIG. 2 is an enlarged left side elevation view of the container securing device.

FIG. 3 is an enlarged right side elevation view of the container securing device; and,

FIG. 4 is an enlarged perspective view of the container securing device.

The container securing device is shown with a symbolic break in its length. The appearance of any portion of the container securing device between the break lines forms no part of the claimed design. The broken lines depicting hook and loop fasteners and triangular hardware indicate portions of the container securing device that form no part of the claimed design.
